UNITED STATES PATENT OFFICE.

MAX PEUKERT, OF TROY, NEW YORK, ASSIGNOR OF ONE-HALF TO TIM & CO., OF TROY, NEW YORK, A COPARTNERSHIP.

MACHINE FOR FOLDING SHIRTS.

SPECIFICATION forming part of Letters Patent No. 694,074, dated February 25, 1902.

Application filed August 28, 1900. Serial No. 28,279. (No model.)

To all whom it may concern:

Be it known that I, MAX PEUKERT, of the city of Troy, county of Rensselaer, and State of New York, have invented new and useful 5 Improvements in Machines for Folding Shirts, of which the following is a specification.

My invention relates to a mechanism for producing and impressing in shirts a fold-line at each side of the bosom, on which when 10 folded the shirts will have a uniformity as regards width and appearance.

Accompanying this specification to form a part of it there are three plates of drawings, containing five figures illustrating the application of my invention, with the same designation of parts by letter reference used in all 15 of them.

Of the illustrations, Figure 1 is a side elevation of the machine, taken at the front. Fig. 2 is a section taken on the line $z-z$ of Fig. 1 with the fold-line presser having been operated to descend, so as to operate upon an inserted shirt. Fig. 3 is an end elevation of the machine with the presser shown as raised. 25 Fig. 4 is a top view of the machine, the fold-line presser having been removed and the position of a shirt upon the bed indicated by a dotted line. Fig. 5 is a top view of the machine.

30 The several parts of the apparatus thus illustrated are designated by letter reference, and the function of the parts is described as follows:

The letters F designate the frame upon 35 which and within which the mechanism is mounted and operated.

The letters B designate the bed on which the shirts in which the fold-lines are to be formed are placed.

40 The letters A designate creaser-bars, of which there is one arranged upon a ledge or shelf b^2 , formed between the ends of and on each side of the bed B.

The letters C designate a fold creaser-blade 45 upwardly projected from each of the creaser-bars A throughout its length. These creaser-bars A are arranged to be adjustably connected to the shelf or ledge on which located, relatively to their distance apart, by means of a 50 slot a^2 , formed oppositely in each of the ledges

or shelves b^2 , and bolts downcast from the under side of each of the creaser-bars, as designated at a^3 , said bolts each passing through one of the slots a^2 and at its lower end provided with a nut n^3 , adapted to extend over 55 the sides of the slot in which it is placed.

The letters G G designate gage-plates, of which there are two arranged upon the bed B, at one end of the latter, and against which the neckband of the inserted shirt S will abut 60 when the shirt is in a proper position to have the fold-lines formed therein. These gage-plates G are adjustably attached to the bed relatively to each other and the creaser-blades C to adapt them to be used with differing 65 sizes of shirts.

The letters g^2 designate a slot formed in each of the plates G, and each of the latter are provided with a screw g^3 , having its head adapted to extend over the sides of the slot in 70 which it is placed and adapted to thread into the bed. This bed-plate B is secured to and supported in the frame F.

The fold presser mechanism M consists of two horizontally-arranged presser-bars P, 75 each having upon its under side the groove v , arranged to be vertically in line with and over one of the blades C of the creaser-bars A. Each of these presser-bars P at each of its ends connects with a plate p^3 , arranged at 80 right angles to the presser-bars and therefrom projected inwardly and laterally toward each other in the same plane. These plates p^3 each adjustably connect to a plate p^4 , arranged beneath them by means of a slot m , 85 formed in each of the plates p^3 , and a screw passing through said slot to be threaded into the plate p^4 beneath. Thus constructed the presser-bars P may be adjusted as to their distance apart and so arranged that each of 90 their grooves v will be vertically in line with and over one of the creasing-blades C. Each of these plates p^4 (to which the presser-bars are attached) at each end of the machine connects with a cross-plate I, forming a part of 95 the presser mechanism.

The letters T^2 designate tube-form slides, of which there are two arranged at each end of the machine, thereat made to pass through one of the cross-bars I and to be secured there- 100

in at t^3 , with a part of the tube-form slides in each instance arranged above and a part below the plate I with which it connects.

The letters d^2 d^2 designate pins, of which 5 there are two outwardly projected from the outer side face of each of the cross-plates I, the function of which will be detailed hereinafter.

The letters R designate four rods, each of 10 which at its lower end is connected to the top of the bed B and in its upward and vertical extension is caused to pass through one of the tube-form slides t^2 and above where passing through the latter to connect with a 15 cross-bar J. As thus constructed and arranged the presser-bars are adapted to be moved downwardly to rest on the creaser-bar blades or moved upwardly therefrom.

The letters L designate a rod which is horizontally placed at the rear and top of the machine to thereat connect at each of its ends 20 with one of the bars J.

The letters K designate clutches, of which 25 there are two at each end of the machine, arranged on the exterior of the frame thereat to be pivoted at k^2 . The lower ends of these clutches below where pivoted are curved inwardly to lap past one another by being cut away on their inner faces at k^3 . Each of the 30 clutches at its upper end is provided with a latch k^4 , the inner edge of the latch being at an upward inclination from the upper arm of the clutch, forming a cam for engagement with the pin d^2 . Wherelapping past each 35 other, each of these clutches is provided with a slot k^5 .

The letter N designates a vertically-placed bar forming a part of the frame at each end of the machine. Each of these bars N is located 40 at the center of the end parts of the frame, and they are each constructed with a centrally-located slot H.

The letters U designate a slide-bar that is horizontally arranged beneath the bed B, and 45 the letter u^2 designates a pin that is laterally projected from each end of this bar U and arranged to enter and pass through the slot H and the slots k^5 in the clutches K at each end of the machine, whereat these clutches lap 50 past each other.

The letters t^3 t^3 designate rods the upper end of each of which is provided with a yoke Y, adapted to receive the bar U and to have the latter pivotally connect therewith, and at its 55 lower end each of the rods t^3 pivotally connects with a bar t^4 of the foot-treadle T³.

The letters S⁴ designate springs connecting the bed B with the foot-treadle, against the recoil force of which the latter is forced down.

60 The letters m^2 designate turnbuckles formed in the rods t^3 .

The letters P⁵ designate pulleys, of which there is one at each end of the machine and thereat centrally mounted upon one of the 65 cross-bars J.

The letters C³ designate cords, of which there is one at each end of the machine hav-

ing one of its ends connecting with one of the plates I thereat to pass therefrom over one of the next adjacent one of the pulleys P⁵ and 70 where extending downwardly therefrom to connect with a weight W³, against the gravity force of which the pressing mechanism is operated to descend upon a shirt placed upon the bed.

The operation of the mechanism thus described and illustrated is as follows: A shirt having been placed upon the bed and in the position indicated by the dotted line d^3 of Fig. 4, the presser mechanism is forced downwardly 80 by hand against the force of the weights W³ and so as to bring the creaser-blades in contact with that part of the shirt in which it is desired to form the fold-lines, with the groove v of the presser-bars also upon the shirt over 85 the blade. This having been done, the foot-treadle is operated to pull downwardly the bar U, which when descending with the pin u^2 at each of its ends outside of where passing through the slot H in the frame at each 90 end of the machine passes also through the slot k^5 of each of the clutches K K where the latter below their pivoted connection with the frame at k^2 lap past each other at each end of the machine. With the pins u^2 thus connected at each end, as the bar U is caused to descend by the action of the treadle each of these pins u^2 will make a cam engagement 95 with the sides of the slots k^5 of each pair of clutches K K at each end of the machine, causing their lower ends to move outwardly from each other on their pivoted connection at k^2 with the upper latch-form ends k^4 of each pair 100 of the clutches caused to move toward each other, and so as to grasp the pins d^2 , projecting from the bars I. The further descent of the bar U therefore necessarily carries the upper ends of the clutches inward and by reason of the inclined or cam form of the latch 105 ends of the clutches applying a pressure to the shirt between the creaser-blades and the groove V to form the fold-lines. On the removal of the pressure of the operator's foot 110 from the treadle the springs S⁴ and the counterpoise-weights W³ raise the upper part of the mechanism from the shirt, restoring it to the position for repeating the operation. With the fold-lines thus well defined the shirts can 115 be folded with uniformity as to width and given a finished appearance.

Having thus described my invention, what I claim, and desire to secure by Letters Patent, is—

1. In a machine for producing fold-lines in a shirt at each side of the bosom the combination with a bed provided with a creaser-blade upwardly projected therefrom at each of its opposite sides, of presser-bars each provided with a groove on its under surface arranged to be vertically over one of the creaser-blades 125 on the bed said presser-bars being provided with a slide at each end of the machine; and means substantially as described whereby said presser-bars are operated to descend 130

upon a shirt placed upon said bed, between said creaser-blades and presser-bar grooves and be operated upon by applied pressure substantially as, and for the purposes set forth.

5 2. In a machine for producing a fold-line in a shirt at each side of the bosom, the combination with a bed provided with neckband gage-plates at one of its ends and having a creaser-bar adjustably connected to a shelf 10 upon each side of said bed, each of said bars being provided with an upcast creaser-blade; and a presser mechanism arranged on vertical slide-ways and having a presser-bar at each side adapted to be laterally adjusted toward 15 or from each other, and each provided with a groove on its under side arranged to be vertically in line with and over one of the creaser-blades, and means substantially as described whereby said presser mechanism is operated 20 to descend upon a shirt placed upon said bed, and have pressure applied thereto to fix the folds therein.

3. The combination with the bed B, having the creaser-blades C, and the vertical side 25 rods R; of the presser mechanism M, having the grooves v, on its under surface vertically in line with, and over said creaser-blades, and at each of its ends provided with a cross-plate I, having outwardly-projecting pins d², 30 d³, and each having tubular slides mounted upon two of the rods R, thereat; a pulley on top of the frame at each end having a cord passed over it with one of its ends attached to one of the plates I, and the other end to a 35 depending weight; clutches K, at each end of the machine pivoted thereto and provided with slots, and a slide-bar U, having a slide-pin u², at each end passing through a slot in the machine-frame and the slots of the 40 clutches thereat; and a foot-treadle connected to said slide-bar constructed and arranged to be operated as, and for the purposes set forth.

4. The combination with the bed B, having 45 bars provided with blades upwardly projected therefrom, and vertical slide-rods at each of its four corners, of the presser mechanism M, having two presser-bars each provided with a groove v, on its under side vertically in line 50 with and over one of the blades of the bed; the end cross-plates I, I, each having on its outer side the pins d², d³, and each connected to one of the ends of the presser mechanism, and each having slides upon two of said slide- 55 rods at each end of the machine; clutches K,

mounted upon each end of the machine; and a slide-bar U, having a pin u², at each end arranged to operate said clutches to grasp the pins upon the cross-plates; and a foot-treadle T³, constructed to operate said slide-bar U, 60 substantially as shown and described.

5. The combination with the bed B, having the creaser-bars A, A, each provided with an upcast creaser-blade C, attached to the frame F, and having at each of its four corners the 65 upcast rod R, of the presser mechanism M, provided with bars P, P, each having a groove v, on its under surface and the cross-plates I, I, each provided with the pins d², d³, outwardly projected therefrom, and at its inner 70 side connected to the presser mechanism; each of said cross-plates having a tubular slide T², at each of its ends mounted upon one of the rods R, on which the presser mechanism can be vertically reciprocated; clutches K, each 75 provided with a latch k⁴, a slot k⁵, and pivoted to the frame at each end at k², and the bar U, having the pin u², at each end arranged to pass through the slot H, in the frame ends, and the slots in the clutches; and 80 the foot-treadle T³, constructed and arranged to be operated substantially as, and for the purposes set forth.

6. The combination with the bed B, having the upcast creaser-blades C, of the presser 85 mechanism M, having the grooves v, on its under side, and the connected cross-plate I, at each end provided with the exteriorly-located pins d², d³, constructed to move vertically on slideways substantially as described; 90 the clutches K, K, at each end of the machine each provided with the latching upper end k⁴, the slot k⁵ and at k², pivoted to the frame end; the slide-bar U having the pin u², at each end arranged to pass through the slot H, 95 in the frame end and the slots in the clutches thereat; whereby when said pressing mechanism is resting on a shirt placed on the bed and the sliding bar U, is drawn downwardly the clutches at each end will grasp the pins 100 d², d³, and thus apply pressure to the presser mechanism, substantially as and for the purposes set forth.

Signed at the city of Troy this 2d day of June, 1900, and in the presence of the two 105 witnesses whose names are hereto written.

MAX PEUKERT.
